CLAIM

The ornamental design for a main body for electronic cigarette as shown and described.

DESCRIPTION

FIG. 1 is a perspective view of a main body for electronic cigarette showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof; and,

FIG. 8 is an enlarged bottom plan view thereof.

The broken lines in the drawings depict portions of the main body for electronic cigarette that form no part of the claimed design. The Oblique lines on the main body for electronic cigarette indicate that those surfaces are transparent.
